UNITED STATES PATENT OFFICE.

WILLIAM L. McGRATH, OF ELMIRA, NEW YORK, ASSIGNOR TO ECLIPSE MACHINE COMPANY, OF ELMIRA, NEW YORK, A CORPORATION OF NEW YORK.

ENGINE STARTER.

Application filed August 2, 1919, Serial No. 314,951. Renewed January 19, 1927.

My invention relates to engine starters and concerns the drive or transmission for transmitting the power of the prime mover or source of power to the member of the engine to be started. In the present instance my invention is shown embodied in a drive of the Eclipse-Bendix type and will be described in connection therewith.

In the type of drive shown a driving member or pinion is mounted on a rotatable member or screw shaft in such manner as to move longitudinally thereof and, rotarily therewith whereby such driving member or pinion is automatically advanced into engagement with the engine member such as the flywheel of the engine and thereupon partakes of rotary movement of the screw shaft to thereby rotate the flywheel and start the engine.

In the usual form of Eclipse-Bendix drive this screw shaft is operatively connected with a driving shaft such as the extended armature shaft of an electric motor or a counter-shaft driven thereby, by means of a coiled driving spring. In the event of the abutting of the pinion teeth against the flywheel teeth end to end the screw shaft will continue to rotate while the pinion is stopped in its longitudinal movement, until such time as the pinion is caused to rotate slightly so as to bring about register between said teeth, whereupon full mesh is obtained.

According to my invention provision is made whereby the screw shaft is normally in driving relationship with the spring driving connection and the driving shaft but is permitted to become disengaged from such driving relationship whenever the said abutment of the pinion teeth and flywheel teeth occurs. According to my present invention the screw shaft will become disengaged under such condition and the pinion will be withdrawn from the flywheel and the starting operation will be repeated automatically until proper mesh between the pinion and the flywheel occurs.

In the drawings, Fig. 1 is a sectional elevation of a starter embodying my invention; Figs. 2 and 3 sections on the lines 2-2 and 3-3 respectively of Fig. 1; and Fig. 4 a view similar to Fig. 1 but showing certain of the parts under the condition of abutment of the pinion teeth and flywheel teeth end to end.

For the purpose of a clear and definite

description of my invention I have shown the same incorporated in a drive of the Eclipse-Bendix type but it is to be understood that my invention in its broader aspect is not limited to this particular type. Moreover while I have shown my invention in connection with a drive of the so-called single reduction type, that is, where the driving shaft is directly driven by the motor and is as usual the extended armature shaft of the motor, my invention is not limited thereto, but is equally applicable to a drive of the double reduction type in which such driving shaft is indirectly driven by the motor.

As shown the motor 1 has a driving shaft 2 which is here the extended armature shaft thereof, provided with a suitable bearing 3 at its outer end. To the inner end of this shaft there is secured by the stud 4 a driving head 5. Another driving head 6 is also mounted on the shaft but is free to float thereon. These two driving heads are operatively connected by means of the coiled driving spring 7, one end of which is secured to the stud 4 and the other end to the stud 8.

Upon the driving shaft 2 is mounted a hollow screw shaft 9 upon which is screw threaded the driving member or pinion 10, the latter being adapted to mesh with the teeth 11 of the engine member such as the flywheel 12. This screw shaft is operatively connected under normal conditions with the driving head 6 for driving the engine member and when rotated thereby the pinion will automatically advance inwardly into mesh with the flywheel teeth and as full mesh is obtained it will rotate with the screw shaft. Thereafter when the engine starts on its own power such pinion will be automatically demeshed.

The driving head 6 and screw shaft 9 are not operatively connected permanently but are operatively connected only under normal conditions. As shown they have clutch engagement by reason of the series of clutch jaws 13 on the driving head 6 and the corresponding clutch jaws 14 on the adjacent end of the screw shaft at a point beyond the stop collar 15 at the inner end of the screw shaft. Such clutch engagement is capable at all normal times of transmitting the torque necessary for the driving operation but is adapted

to be released in the event that the longitudinal movement of the pinion is interrupted. The release of the clutch is therefore under the control of the driving member or pinion.

5 The longitudinal travel of the pinion 10 is made against the tension of a light coil spring 16 which encircles the outer end of the screw shaft and has one end 17 secured to the weight portion 18 of the weighted disk of the pinion, and its other end 19 secured by means of the screw 20 to the sleeve 21 which is secured to the outer end of the screw shaft. When the pinion moves inwardly towards the flywheel this coil spring 10 will become extended and wound up as shown in Fig. 4 it being understood that such spring 15 is so light that it will not interfere with this advancing longitudinal movement of the pinion when the screw shaft is positively rotated for the starting operation.

Under normal conditions the driving head 6 and the screw shaft are operatively connected by means of the clutch and such connection remains whenever proper register occurs between the pinion teeth and the flywheel teeth. If, however, the teeth 10 of the pinion abut the flywheel teeth 11 end to end, the pinion is stopped in its longitudinal 20 movement with reference to the screw shaft, and as the clutch jaws 13-14 are in engagement, the screw shaft will continue to rotate, thereby carrying the screw shaft to the left against the pressure of the spring 22 until 25 the clutch jaws 13-14 are out of engagement. The pressure of the pinion against the flywheel at this time will be comparatively light. The torsion spring 16 being now wound up to an appreciable extent, its 30 tendency will be either to rotate the screw shaft within the pinion, carrying said screw shaft to the right, or to rotate the pinion on the screw shaft, carrying said pinion to the left. It is conceivable that owing to the friction of the screw shaft with shaft 2, and the 35 fact that the pinion has manifestly abutted the teeth with comparatively slight pressure, that the pinion may rotate on the screw shaft first, thereby returning to normal or home 40 position thereon, and at substantially the same time the spring 22 will urge the screw shaft toward the right until the clutch jaws 13 and 14 contact in whichever position they 45 happen to align at the moment, unless the pinion teeth again contact the flywheel teeth 50 before the clutch jaws 13-14 contact, in which latter case the described operation will be repeated. In case the spring 16 should turn the pinion slightly so as to occasion 55 register between the teeth and the spring 22 should then act instantly before the spring 16 has been able to withdraw the pinion to home position, such teeth will mesh and the clutch jaws will be re-connected for 60 driving purposes. However, should friction 65

conditions be such that the tendency is to urge the screw shaft to the right, the spring 16 causing it to rotate in the pinion, the longitudinal movement of the screw shaft will be similarly stopped on contact of the 70 clutch jaws 13 and 14 longitudinally, and the remainder of the tension of the spring 16 will retract the pinion from contact with the flywheel teeth.

It will thus be seen that regardless of the 75 exact sequence of operations or of varying frictional conditions present, the desired function of the structure as shown is accomplished.

Thus the device will operate automatically 80 without damage or injury to the parts until perfect mesh is obtained with the engine member. It is evident that no load can be applied until the conditions are such as to permit of proper starting and therefore all 85 parts are protected from damage and perfect functioning is insured.

The driving member is in the present case 90 a pinion adapted to mesh directly with the engine member but it will be understood that this invention is not limited directly to this type of driving member and also that such invention may be incorporated in that type of drive in which the member screw threaded on the screw shaft is a control member which 95 controls the actual driving member that engages directly with the engine member. Moreover it will be understood that the drive spring while of the same general character as that in use in the Eclipse-Bendix drive 100 must in this instance be wound opposite to the direction of the thread of the screw shaft. For instance, in the present case, a right hand spring is employed with a left hand thread on the screw shaft. Furthermore, damage to the parts is prevented in case 105 of any extraneous obstruction to the travel of the pinion, as might occur from a loose bolt in the adjacent housing or supporting parts.

110 I claim:

1. The combination of a driving element, a rotatable shaft, a driving member mounted on the shaft for longitudinal movement thereof and rotary movement therewith, and means which normally connect said element and shaft together for transmitting the torque for the driving operation but adapted to be operated to disconnect them when the longitudinal movement of the driving member is interrupted.

2. The combination of a driving element, a rotatable shaft, a driving member mounted on the shaft for longitudinal movement thereof and rotary movement therewith, and a clutch which normally connects said element and shaft together for transmitting the torque for the driving operation but adapted to be released when the longitudinal movement of the driving member is interrupted.

3. The combination of a driving element, a rotatable screw-shaft, a driving member threaded on the screw-shaft for longitudinal movement thereof and rotary movement therewith, and means which normally connect said element and shaft together for transmitting the torque for the driving operation but adapted to be operated to disconnect them, and a spring for normally maintaining said driving connection through said connecting means but adapted to yield to permit the release thereof. 70
4. The combination of a driving element, a rotatable shaft, a driving member mounted on the shaft for longitudinal movement thereof and rotary movement therewith, and means which normally connect said element and shaft together for transmitting the torque for the driving operation but adapted to be operated to disconnect them, said disconnection of the element and shaft being under the control of the driving member in its longitudinal movement. 75
5. The combination of a driving element, a rotatable shaft, a driving member mounted on the shaft for longitudinal movement thereof and rotary movement therewith, and a clutch which normally connects said element and shaft together for transmitting the torque for the driving operation and the release of which is under the control of the driving member in its longitudinal movement. 80
6. The combination of a driving element, a rotatable shaft, a driving member mounted on the shaft for longitudinal movement thereof and rotary movement therewith, means which normally connect said element and shaft together for transmitting the torque for the driving operation but adapted to be operated to disconnect them, and resilient means for returning the driving member to normal position on the shaft. 85
7. The combination of a driving element, a rotatable shaft, a driving member mounted on the shaft for longitudinal movement thereof and rotary movement therewith, means which normally connect said element and shaft together for transmitting the torque for the driving operation but adapted to be operated to disconnect them, and a spring connected with the shaft and driving member for returning the latter to normal position on the shaft. 90
8. The combination of a driving element, a rotatable shaft, a driving member mounted on the shaft for longitudinal movement thereof and rotary movement therewith, means which normally connect said element and shaft together for transmitting the torque for the driving operation but adapted to be operated to disconnect them, and yielding means for normally maintaining said driving connection through said connecting means but adapted to yield to permit the release thereof. 95
9. The combination of a driving element, a rotatable shaft, a driving member mounted on the shaft for longitudinal movement thereof and rotary movement therewith, means which normally connect said element and shaft together for transmitting the torque for the driving operation but adapted to be operated to disconnect them, and a spring for normally maintaining said driving connection through said connecting means but adapted to yield to permit the release thereof, and resilient means for returning the driving member to normal position on the shaft. 100
10. The combination of a driving element, a rotatable shaft, a driving member mounted on the shaft for longitudinal movement thereof and rotary movement therewith, means which normally connect said element and shaft together for transmitting the torque for the driving operation but adapted to be operated to disconnect them, means for normally maintaining said driving connection through said connecting means but adapted to yield to permit the release thereof, and resilient means for returning the driving member to normal position on the shaft. 105
11. The combination of a driving element, a rotatable screw-shaft, a driving member threaded thereon for longitudinal movement thereof and rotary movement therewith, a clutch normally connecting said element and shaft for transmitting the torque for the driving operation, a spring for normally holding the clutch in operative condition but adapted to yield to release such clutch, and a spring connected with the shaft and driving member for returning the latter to normal position on the shaft. 110
12. The combination of a driving element, a rotatable screw-shaft, a driving member threaded thereon for longitudinal movement thereof and rotary movement therewith, a clutch normally connecting said element and shaft for transmitting the torque for the driving operation, a spring for normally holding the clutch in operative condition but adapted to yield to release such clutch, and a spring connected with the shaft and driving member for returning the latter to normal position on the shaft. 115
13. The combination of a driving element, a rotatable screw-shaft, a driving member threaded thereon for longitudinal movement thereof and rotary movement therewith, a clutch normally connecting said element and shaft for transmitting the torque for the driving operation, a spring for normally holding the clutch in operative condition but adapted to yield to release such clutch, and a spring connected with the shaft and driving member for returning the latter to normal position on the shaft, said screw-shaft being mounted to move longitudinally. 120
14. The combination of a driving element, a rotatable screw-shaft, a driving member threaded thereon for longitudinal movement thereof and rotary movement therewith, a clutch normally connecting said element and shaft for transmitting the torque for the driving operation, a spring for normally holding the clutch in operative condition but adapted to yield to release such clutch, and a spring connected with the shaft and driving member for returning the latter to normal position on the shaft, said screw-shaft being mounted to move longitudinally. 125
15. The combination of a driving element, a rotatable screw-shaft, a driving member threaded thereon for longitudinal movement thereof and rotary movement therewith, a clutch normally connecting said element and shaft for transmitting the torque for the driving operation, a spring for normally holding the clutch in operative condition but adapted to yield to release such clutch, and a spring connected with the shaft and driving member for returning the latter to normal position on the shaft, said screw-shaft being mounted to move longitudinally. 130

against the tension of the first-named spring when the longitudinal movement of the driving member is interrupted.

14. The combination of a driving element, 5 a rotatable shaft, said element and shaft being arranged co-axially and having at their adjacent ends cooperating clutch members adapted to transmit all the torque for the driving operation, and a driving member 10 mounted on the shaft for longitudinal movement thereof and rotary movement therewith, said clutch members being adapted to be disconnected when the longitudinal movement of the driving member is interrupted.

15. The combination of a driving element, 15 a rotatable shaft, said element and shaft being arranged coaxially and having at their adjacent ends complementary clutch jaws which are normally engaged to transmit all 20 the torque for the driving operation, and a driving member mounted on the shaft for longitudinal movement thereof and rotary movement therewith, said clutch jaws being adapted to be disconnected when the longitudinal 25 movement of the driving member is interrupted.

16. The combination of a yieldingly driven driving head, a rotatable shaft normally operatively connected with said head for transmitting the torque for the driving operation but adapted to be disconnected therefrom upon relative longitudinal movement of said head and shaft one with respect to the other, and a driving member mounted on the shaft 35 for longitudinal movement thereof and rotary movement therewith.

17. The combination of a driving element, 40 a rotatable shaft, said element and shaft being arranged co-axially and being normally operatively engaged for driving but one being movable axially for disengagement, and a driving member mounted on the shaft for longitudinal movement thereof and rotary movement therewith.

18. The combination of a rotatable driving element having a clutch member, a rotatable screw shaft having at one end a stop means and terminating in a corresponding clutch member, which clutch members are 45 normally engaged, and a driving member screw threaded on the shaft for longitudinal movement thereof and rotary movement therewith when in contact with said stop means, said shaft being mounted to slide longitudinally to disengage said members when said longitudinal movement of the driving member is interrupted.

19. The combination of a rotatable driving shaft, a driving element mounted to float 50 thereon, a yielding driving connection between it and the shaft, a rotatable driven shaft normally operatively connected with such element but adapted to be disconnected

therefrom, and a driving member mounted on the shaft for longitudinal movement 65 thereof and rotary movement therewith.

20. The combination of a rotatable driving shaft, a driving element mounted to float thereon, a yielding driving connection between it and the shaft, a rotatable driven shaft normally operatively connected with such element but adapted to be disconnected therefrom, said driven shaft being hollow and mounted on the driving shaft, and a driving member mounted on the driven shaft 75 for longitudinal movement thereof and rotary movement therewith.

21. The combination of a rotatable driving shaft, a driving element mounted to float thereon, a yielding driving connection 80 between it and the shaft, a rotatable driven shaft normally operatively connected with such element but adapted to be disconnected therefrom, said driven shaft being a hollow screw shaft mounted on the driving 85 shaft, and a driving member screw threaded on the screw shaft for longitudinal movement thereof and rotary movement therewith.

22. The combination of a rotatable driving 90 shaft, a driving head in the form of a sleeve loosely mounted thereon and having clutch jaws at one end, a yielding driving connection between the shaft and head, a hollow screw shaft mounted on the driving shaft 95 and having a longitudinal movement thereon, said screw shaft having at one end clutch jaws normally in engagement with the other clutch jaws, and a driving member screw threaded on the screw shaft for longitudinal 100 movement thereof and rotary movement therewith.

23. The combination of a driving element, a rotatable shaft, a driving member mounted on the shaft for longitudinal movement 105 thereof and rotary movement therewith, and means which normally connect said element and shaft together for transmitting the torque for the driving operation but adapted to be operated to disconnect them by 110 relative longitudinal movement of such element and shaft one with respect to the other.

24. The combination of a driving element, a rotatable shaft mounted for rotary and 115 longitudinal movement, a driving member mounted on the shaft for longitudinal movement thereof and rotary movement therewith, and means which normally connect said element and shaft together for 120 transmitting the torque for the driving operation but adapted to be operated to disconnect them when said shaft is moved longitudinally.
